United States Patent Office.

JOHN RAMSBURGH, SR., OF NEW MADRID, MISSOURI.

Letters Patent No. 82,873, dated October 6, 1868.

IMPROVED MEDICAL COMPOUND.

The Schedule referred to in these Letters Patent and making part of the same.

TO ALL WHOM IT MAY CONCERN:

Be it known that I, JOHN RAMSBURGH, Sr., of New Madrid, in the county of New Madrid, in the State of Missouri, have invented and discovered a new remedy for the cure of consumption and all lung diseases, and that the following is a full and exact description thereof.

The discovery or remedy consists of the following compound: Spikenard, elecampane, and comfrey, in equal parts; Indian turnip, half part. Mix with honey and whiskey, thus making a strong compound or bitter.

This compound, in these proportions, has proved an excellent cure for many persons afflicted with diseases of the lungs. In several cases, when the patient has exhausted travel and various remedies prescribed by eminent physicians, this remedy has been used with entire success. I have not yet known it to fail.

What I claim, therefore, as my invention, and desire to secure by Letters Patent, is—

The improved medicine, prepared of the materials and substances as set forth.

JOHN RAMSBURGH.

Witnesses:

JOHN T. SCOTT,

WM. J. DENHART.
